NESTING CHAIR

Charles Eames and Don Albinson, Venice, and Dale W. Bauer, Los Angeles, Calif., assignors to Herman Miller Furniture Company, Zeeland, Mich., a corporation of Michigan

Application March 5, 1956, Serial No. 569,424

11 Claims. (Cl. 155—2)

This invention relates to furniture construction and more particularly to an improved chair. This invention also applies to improved chairs capable of being vertically stacked one on another for storage purposes and which can be joined together in orderly rows when in use.

The chair of this invention is suitable for public seating use, such as auditoriums, schools, meeting houses, and churches. In such institutional applications it is desirable to use a large group of chairs which can be temporarily placed and then removed for compact storage. Chairs suitable for this use are of numerous types and designs. One type is the folding chair. Another is adapted to being stacked one on another in vertical columns without folding. The stacking type of chair is preferable over the folding type because of its comfort. However, stacking chairs have not found ready acceptance because they lack certain essential features.

One disadvantage of stacking chairs is that they are usually heavier than folding chairs because of the structure required to stack them one on another. If the structure for supporting the chairs in a vertical stack is not sufficiently strong it will not bear the load of the chairs it supports. Thus, stacking chairs have been considered either too heavy, too cumbersome for stacking vertically, or not sufficiently strong for making a high vertical stack. This invention is directed to providing a chair which is comparatively light and adapted both in strength and stability for stacking purposes.

Another object of this invention is to provide chairs which can be easily and temporarily joined together, thus, automatically controlling their alignment and spacing.

A further object of this invention is to provide a light-weight yet strong and comfortable chair requiring a minimum of servicing since it is not readily subject to damage or breakage.

A still further object of this invention is to provide a chair having a supporting frame constructed of a minimum number of parts, thus being capable of easy fabrication, assembly, handling, and replacement of parts.

Still another object of this invention is to provide a construction for chairs permitting the chairs to be compactly stacked one upon another. The stacks formed by these chairs are relatively stable, thus reducing the danger of the stack's collapsing or tipping over.

Another object of this invention is to provide chairs having a simple means for locking them together without the use of tools.

Other objects of our invention will become obvious upon reading the following specification in conjunction with the accompanying drawings wherein:

Fig. 1 is an oblique side elevational view of the chair.

Fig. 2 is a partial, side elevational view of the chair showing the supporting and locking structure.

Fig. 3 is a fragmentary, front, elevational, sectional view of a hook taken along the plane III—III of Fig. 2.

Fig. 4 is a fragmentary, front elevational, sectional view of a loop taken along the plane IV—IV of Fig. 6.

2

Fig. 5 is a fragmentary, front elevational view of the side legs of two chairs illustrating the means for hooking chairs together.

Fig. 6 is a fragmentary, side elevational view of the supporting structure illustrating a leg brace having a loop extending therefrom.

Fig. 7 is a plan view of the supporting structure for the chair seat showing the seat in phantom.

Fig. 8 is a fragmentary, side elevational view of two chairs stacked one upon another.

Briefly, this invention concerns chair construction. The construction is simple including identical front and rear leg structures, each having a pair of legs connected together at the top by a cross piece. The seat of the chair is supported by these cross pieces. A brace is fixedly secured to each side between the front and rear legs. The side braces are secured to the legs at points spaced outwardly from the marginal side edges of the seat. Thus the legs are permitted to pass on each side of the marginal edges of the seat. The leg braces extend outwardly from the outer sides of the legs to provide a supporting surface on which corresponding leg braces can rest. Thus, the seats can be stacked, one upon another, to form a compact and stable stack of chairs.

Throughout this specification, in describing the chair the words "inwardly" and "outwardly" are used. "Inwardly" shall be taken to mean away from the center of the seat. "Front" means toward the front of the chair or to the left as shown in Fig. 2. "Rearward" of the chair means towards the back of the chair or to the right as shown in Fig. 2. Other terms such as "horizontal" and "vertical" are used as meaning horizontal or vertical to the floor or surface on which the chair rests.

Referring to the drawings reference numeral 1 indicates one of the chairs including the seat or shell 10 and the support structure 20.

The shell 10 is of a reinforced synthetic fibre resin. It is molded under heat and pressure to give the desired shape. Preferably the edges are additionally reinforced to prevent splitting. The resins most conventionally used are polyesters of various colored pigmentation. The fibres most commonly used are filamentary glass. The shell 10 is shaped to conform to the body contour of an average person. The material is somewhat resilient making the chair comfortable.

The plastic material from which the chair is made is relatively light. It is not readily subject to damage or breakage because of its resiliency. It has high impact and surface abrasion resistance. Changes in moisture content of the air will not affect it. It is vermin proof and may be readily cleaned with soap and water or a damp cloth.

The base or supporting frame 20 includes a front standard or leg structure 21 and a rear standard or leg structure 22. Each of these structures is identical. Each is formed from a single piece of tubular metal. The front leg structure 21 includes the two legs 23 and 24 joined at the top by a cross piece consisting of the downwardly and inwardly extending side portions 25 and the intermediate horizontal straight portion 26 (Figs. 1 and 7). The rear leg structure 22 consists of the two rear legs 27 and 28 connected at their tops by the cross piece including the downwardly extending end portions 29 and the horizontal intermediate portion 30.

Mounting straps 31 are secured by welding or any other suitable means to the cross pieces of the front and rear leg structures 21 and 22. The mounting straps 31 are secured to the downwardly extending end portions 25 and 29 immediately adjacent the point where the end portions merge with the intermediate straight portions 26 and 30. The ends of the mounting straps are bent upwardly and

slightly twisted to provide a supporting surface conforming with the contoured bottom surface of the shell 10. Holes 32 are provided in the ends of the mounting straps through which a screw can be inserted for securing the seat to the mounting straps and thus to the supporting frame.

The mounting straps 31 are secured to the circular shock mounts 33 which preferably are adhesively secured to the bottom of the shell. Shock mounts 33 each have an internally threaded female insert adapted to receive a screw. This shock mount is of similar construction to that described and claimed in Patent No. 2,647,136.

In the preferred form of this invention, the front legs 23 and 24 extend downwardly and forwardly. The rear legs 27 and 28 extend downwardly and rearwardly. The legs are held and supported in this position by the leg braces 40 secured to the outer sides of the legs and by the straps 31. The leg braces 40 are fabricated of a heavy gauge wire formed into an elongated ring.

A loop 41 is secured to one of the braces 40 (Figs. 4 and 7). It extends outwardly from the brace and is adapted to receive a hook 42 mounted to the other brace 40 (Figs. 2, 3 and 5). The loop 41 is a U-shaped, heavy gauge wire secured to the top cross wire 43 of one of the rings 40 (Fig. 4). The hook 42 is also a heavy gauge wire having two legs 44 parallel to each other and connected by the U-shaped hook 45. The hook 45 extends outwardly from the legs. The legs 44 are secured to the top and bottom cross wires of one of the rings 40. The width of both the loop 41 and the hook 45 is such that the hook 45 fits within the loop (Fig. 5). The loop 41 and hook 42 are secured to their respective braces 40 by a resistance weld or any other suitable means.

The entire supporting frame 20 may be of aluminum or any other material but it is more commonly of tubular steel. The side braces are usually of a steel wire however aluminum or any other suitable material can be used. The mounting straps can be made of any suitable material. All of these parts can be suitably plated as with chrome. The shock mounts 33 are of rubber or any other resilient material.

The assembled chair

It should be evident that the chair of this invention is made with a minimum number of parts. These include the identical front and rear leg structures 21 and 22, the shell 10, the mounting straps 31, the shock mounts 33 and the side leg braces 40 are also identical except for the means for joining two or more chairs together. The supporting frame 20 is preferably of an all welded construction and it is secured to the shell by screws 47.

The assembled supporting structure is best shown in Figs. 1 and 7. The front and rear leg structures 21 and 22 are arranged with the front legs 23 and 24 extending downwardly and forwardly. The rear legs 27 and 28 extend downwardly and rearwardly. The cross pieces 26 and 30 are spaced one from another (Fig. 7) and are held in that position by the mounting straps 31 secured thereto by welding or any other suitable means. The forward and rearward positions of the legs are maintained by the side braces 40, secured at their side portions to the front and rear legs. This attachment is made by welding or any other suitable means. The hook 42 and loop 41 extend outwardly from the side braces.

The shock mounts 33 are adhesively secured to the bottom surface of the seat 10 at points which will permit a screw passing through the hole 32 of the mounting strap to be secured in the internally threaded female insert of the shock mount. With these shock mounts 33 properly located, the seat is placed on the shock mounts with the internally threaded female inserts aligned with the holes 32. The screws 47 extending through holes 33 are threaded into the inserts of the shock mounts, securing the seat to the supporting frame 20.

The width of the supporting frame, that is the width of the front and rear leg structures, and the lateral posi-

tioning of the side leg braces relative to the side marginal edges of the seat 10 are important. Fig. 7 illustrates this relationship. The support frame 20 is shown wider than the seat. This is necessary to permit the frame to pass over the seat or shell 10 of another seat.

The vertical spacing of the side braces 40 is important. Both the upper and lower limits of their vertical position on the legs is established at the point which provides effective cross-bracing for the legs and at the same time provides a means for supporting a chair stacked above it. The side braces index the chairs providing a vertical and stable stack in such a manner that the chair shells are spaced from one another and from the frames for protecting the shells against abrasion.

In the preferred form the angular relationship of the legs to each other and their lateral spacing is limited only by two factors. The legs must be able to pass about the shell 10 to permit stacking and the legs of one chair must not spread laterally sufficiently to interfere with the joining of one chair to another. However, where the loop and hook arrangement is not used and the chairs are not to be joined, this latter limitation does not apply.

The position and shape of the side leg braces are important. The braces are elongated and secured to the legs at approximately the same vertical position one-third down the legs. In other words the points of attachment of the leg braces to the legs lie substantially in horizontal plane. This gives symmetry to the chair and at the same time contributes to the stability of a stack formed by such chairs. The side braces, being located approximately one-third down the leg, provide a support surface on which the brace of the upper chair can rest upon the brace of the chair beneath. This support surface is long enough in a horizontal direction to prevent the stacked chairs from tipping forward or backwardly.

When the chairs are stacked one upon another as shown in Fig. 8, the bottom cross-piece of the side braces 40 of one chair rests directly on the top cross-piece of the side braces of the chair beneath it. The side braces 40 have an adequate cross-section so that they extend a sufficient distance outwardly from the leg to provide an adequate supporting surface.

A plurality of these chairs may be joined together, while in use, depending upon the wishes of the user. If they are to be joined, the user simply lifts one chair a short distance and engages the hook 45 into the loop 41 of the adjacent chair. Any number of chairs can be hooked together in this fashion. When joined together, the spacing and alignment of the chairs is automatically determined. This has several obvious advantages. On the other hand, the chairs can be used individually and despite the joining feature, have a pleasing appearance.

It is significant that the braces on the side of the legs serve several functions while at the same time giving a good and pleasing appearance to the chair. The braces provide means for joining several chairs together in orderly manageable rows. They serve as braces for the legs. They index, support, and provide clearance for the various components of the chair when stacked in vertical rows.

The plastic seat of this chair is more attractive than conventional chairs designed for temporary use and stored. It requires no maintenance such as re-upholstering or spring replacement.

After the chairs have been used and it is desired to store them in a compact storage area, the chairs are quickly separated simply by lifting and stacking one on another in a manner shown in Fig. 8. The leg braces rest on each other, maintaining positive spacing between the shells and preventing any scratching or marring of the shells. At the same time, a compact stack of chairs is obtained since the side braces, collectively, form a supporting column on each side of the stack. Because of the strength of the chair and the features previously de-

scribed, the stack is stable allowing the stack to be made relatively high without danger of tipping or collapsing.

Another advantage of this invention is the structural disassociation of the leg structure or base from the seat structure. Should either be damaged, it alone may be replaced without the expense of purchasing the other component. The substitution is both quick and simple since only the four screws 47 are involved.

Having described our invention, it should be realized that there is provided a simple, strong and lightweight chair made with a minimum of parts adapted to quick and inexpensive mass assembly methods. The chair can be used with other chairs and locked thereto for forming straight rows of chairs and for preventing the chairs from being dispersed throughout the entire hall in which they are being used.

It should be understood that in describing this invention certain features have been described which do not necessarily constitute a part of this invention. Further, various other embodiments can be made of this invention which will be entirely within the spirit of this invention. These embodiments and modifications are covered by this invention unless the appended claims expressly state otherwise.

We claim:

1. A chair construction comprising: a seat; a front leg structure including a pair of legs connected together at the top by a cross piece; a rear leg structure identical to said front leg structure; said front and rear leg structures being operatively secured at said cross pieces to the under side of said seat for supporting said seat; and a pair of substantially identical braces fixedly secured to and extending between said front and rear legs, said braces forming vertically spaced upper and lower bearing surfaces extending laterally outwardly from said legs, said upper bearing surfaces forming supports on which the lower bearing surfaces of the leg braces of an identical chair seat when two of the chairs are stacked with the legs and feet of the chairs slightly spaced vertically.

2. A chair construction comprising: a seat; a front leg structure including a one piece tube bent to form a pair of legs connected together at the top by a cross piece; a rear leg structure identical to said front leg structure; said front and rear leg structure being operatively secured to the under side of said seat at said cross pieces for supporting said seat; and a pair of substantially identical ring-shaped, elongated, wire braces fixedly secured to and between said front and rear legs, said ring shaped braces having spaced upper and lower sections forming vertically spaced upper and lower bearing surfaces extending laterally outwardly from said legs, said upper bearing surfaces of said upper sections forming supports on which the lower bearing surfaces of said lower sections of the leg braces of an identical chair seat when two of the chairs are stacked with the legs and feet of the chairs slightly spaced vertically.

3. A chair construction comprising: a seat having marginal side edges; a pair of front legs and a pair of rear legs secured to and supporting said seat; a pair of side braces; said front legs being disposed at an angle to said rear legs whereby the legs of said chair may be vertically telescoped over the legs of an identical chair; said braces being secured to said inclined legs forming an A-shaped support on each side of said chair; said A-shaped support being offset laterally outwardly of said marginal side edges of said seat; said braces being extended outwardly of said legs and vertically positioned on said legs between the upper and lower portions of said legs; said braces forming vertically spaced upper and lower bearing surfaces extending laterally outwardly from said legs; said upper bearing surfaces forming supports on which the lower bearing surfaces of the leg braces of an identical chair seat when two of the chairs are stacked with the legs and seat of the chairs slightly spaced vertically.

4. In a furniture base construction adapted to be stacked one upon another in columns, said base comprising: four leg elements inclined from each other whereby the legs of said base may be vertically telescoped over the legs of an identical base; means rigidly securing said leg elements together at the upper end of said base; said leg elements being grouped into two pairs, one on each side of said base; said legs having inner and outer sides; a brace member extending between and rigidly secured to each leg of each of said pairs between the upper and lower portions of said leg elements; said braces extending beyond said outer sides of said legs and parallel to the plane of the lower ends of said leg elements; said braces having vertically spaced upper and lower bearing surfaces extending outwardly beyond the outer sides of said legs; said upper bearing surfaces forming supports on which the lower bearing surfaces of the leg braces of an identical base seat when two of the bases are stacked with the corresponding legs of the bases slightly spaced vertically.

5. In a furniture base construction adapted to be stacked one upon another in columns, said base comprising: a pair of inverted U-shaped standards, the sides of said standards forming legs; said standards converging at their upper ends and means rigidly securing said standards together at said upper ends; a brace member extending between said standards one on each side thereof; said braces being external of said base and parallel to the plane of the lower ends of said legs; said braces forming vertically spaced upper and lower bearing surfaces extending laterally outwardly from said legs, said upper bearing surfaces forming supports on which the lower bearing surfaces of the leg braces of an identical chair seat when two of the chairs are stacked with the legs and feet of the chairs slightly spaced vertically.

6. In a furniture base construction adapted to be stacked one upon another in columns, said base comprising: a front leg structure bent into an inverted generally U-shape to form a laterally extending top cross member and a pair of legs; a rear leg structure identical to said front leg structure; said front and rear leg structures converging upwardly and means connecting said cross members of said front and rear leg structures; a pair of side braces, each extending between and secured to a front and a rear one of said legs and spaced from both the upper and lower ends of said legs; said side braces forming vertically spaced upper and lower bearing surfaces extending outwardly from said legs, said upper bearing surfaces forming supports on which the lower bearing surfaces of the leg braces of an identical base seat when two of the bases are stacked with the corresponding legs of the bases vertically spaced.

7. In a furniture base construction adapted to be stacked one upon another in columns, said base comprising: a front leg structure bent into an inverted generally U-shape to form a laterally extending top cross member and a pair of parallel legs; a rear leg structure identical to said front leg structure; said front and rear leg structures converging upwardly and means connecting said cross members of said front and rear leg structures; a pair of side braces, each extending between and secured to a front and a rear one of said legs and spaced from both the upper and lower ends of said legs; said braces forming vertically spaced upper and lower bearing surfaces extending outwardly from said legs, said bearing surfaces forming supports on which the lower bearing surfaces of the leg braces of an identical base seat when two of the bases are stacked with the corresponding legs of the bases vertically spaced.

8. In a furniture base construction adapted to be stacked one upon another in columns, said base comprising: a front leg structure bent into an inverted generally U-shape to form a laterally extending top cross member and a pair of parallel legs; a rear leg structure identical to said front leg structure; said front and rear leg struc-

tures converging upwardly and means connecting said cross members of said front and rear leg structures; said legs each having inner and outer surfaces; a pair of side braces, each extending between and secured to a front and a rear one of said legs and vertically spaced from both the upper and lower ends of said legs; said side braces forming vertically spaced upper and lower bearing surfaces extending outwardly from said legs; said braces having inner surfaces spaced laterally of said base a distance equal to the lateral spacing of said outer surfaces of said legs; said upper bearing surfaces of said braces forming supports on which the lower bearing surfaces of the leg braces of an identical base seat when two of the bases are stacked with the corresponding legs of the bases spaced vertically and the inner surfaces of the braces of the identical base being cooperative with the outer surfaces of the legs of said base for limiting relative lateral movement of the bases with respect to each other.

9. A chair base construction adapted to be stacked one upon another in columns, said base comprising: a front leg structure bent into an inverted generally U-shape to form a laterally extending top cross member and a pair of parallel legs; a rear leg structure identical to said front leg structure; said front and rear leg structures converging upwardly and means connecting said cross members of said front and rear leg structures; a seat secured to said connecting means, the side margins of said seat being spaced inwardly from said legs; a pair of side braces, each extending between and secured to a front and a rear one of said legs and spaced from both the upper and lower ends of said legs; said side braces forming vertically spaced upper and lower bearing surfaces forming supports on which the lower bearing surfaces of the leg braces of an identical chair base seat when two of the bases are stacked with the corresponding legs and seats of the chairs vertically spaced.

10. A chair construction comprising: a seat having a pair of legs on each side thereof extending therefrom to support said seat; said legs in a front and back direction

20 30 35 40

converging toward said seat and laterally of said seat being parallel; said legs having outer and inner sides; a pair of leg braces, one of said braces extending between and secured to both legs of each of said pairs of legs between said seat and the lower ends of said legs; said leg braces having vertically spaced upper and lower bearing surfaces extending outwardly beyond said outer sides of said legs, said upper bearing surfaces forming supports on which the lower bearing surfaces of leg braces of an identical chair seat when two of the chairs are stacked with the legs and seats of the chairs slightly spaced vertically.

11. A chair construction comprising: a seat having a pair of legs on each side thereof extending therefrom to support said seat, said legs being inclined from each other whereby the legs of said chair may be vertically telescoped over the legs of an identical chair; said legs having inner and outer sides; a pair of leg braces, one of said braces extending between and secured to both legs of each of said pairs of legs and vertically spaced from both said seat and the lower ends of said legs; said leg braces having upper and lower bearing surfaces extending outwardly from the outer sides of said legs, said upper bearing surfaces forming supports on which the lower bearing surfaces of leg braces of an identical chair seat when two of the chairs are stacked with the legs and seats of the chairs slightly spaced vertically.
